DESIGN.

—o—

M. MELLINGER.

FRIEZE DECORATION.

No. 17,745.

Patented Sept. 27, 1887.

UNITED STATES PATENT OFFICE.

MICHEL MELLINGER, OF NEW YORK, N. Y., ASSIGNOR TO WARREN, LANGE & CO., OF SAME PLACE.

DESIGN FOR FRIEZE DECORATION.

SPECIFICATION forming part of Design No. 17,745, dated September 27, 1887.

Application filed August 22, 1887. Serial No. 247,617. Term of patent 3½ years.

To all whom it may concern:

Be it known that I, MICHEL MELLINGER, a citizen of France, residing in New York city, in the county and State of New York, have invented a new and original Design for Frieze Decorations, of which the following is a specification, reference being had to the accompanying photograph, which forms a part of the same.

10 The invention relates to a design for a frieze shown on paper or similar articles; and it consists in the novel configuration and grouping of figures herein specifically shown and claimed.

15 The accompanying photograph is a face view of paper showing my new design.

My frieze has a lower ornamental border, above which is a row of large conventionalized figures, occurring at regular intervals and having a general triangular shape. The middle

portion of the frieze is ornamented with a series of arching lines intersecting one another, and thus forming a lattice-work. Parallel with and similar in arrangement to this series of arches is a second series of arches less prominent than the former and increasing the lattice-like effect. Running lengthwise of the design and underlying the lattice-work are ornamental bands, some with scalloped edges. In the spaces formed at the base of the arches are other ornamental figures. The frieze has a narrow outer margin with ornamental figures.

What I claim as new, and desire to secure by Letters Patent, is—

20 The design for a frieze, consisting of the design substantially as shown.

MICHEL MELLINGER.
